DESIGN FOR A GLASS BOTTLE

Lawrence J. Kihn, Pittsburgh, Pa., assignor to J. T. & A. Hamilton Company, a corporation of Pennsylvania

Application May 31, 1934, Serial No. 51,979

Term of patent 14 years

To all whom it may concern:

Be it known that I, Lawrence J. Kihn, a citizen of the United States, residing in Pittsburgh, in the county of Allegheny, and State of Pennsylvania, have invented a new, original, and ornamental Design for a Glass Bottle, of which the following is a specification, reference being had to the accompanying drawing, forming part thereof.

My design relates to the general appearance of the glass bottle, as produced by its conformation and external ornamentation.

In the drawing: Fig. I is a side elevation of a glass bottle showing my new design; and Fig. II is a plan view of the glass bottle.

I claim:

The ornamental design for a glass bottle, substantially as shown.

LAWRENCE J. KIHN.
